UNITED STATES PATENT OFFICE.

GEROLAMO CATANZANO, OF SOMERVILLE, MASSACHUSETTS.

METHOD OF MOUNTING PROPELLERS UPON SHIPS.

1,317,861.

Specification of Letters Patent.

Patented Oct. 7, 1919.

Application filed January 17, 1919. Serial No. 271,684.

To all whom it may concern:

Be it known that I, GEROLAMO CATANZANO, a citizen of the United States, and resident of Somerville, county of Middlesex, and 5 Commonwealth of Massachusetts, have invented an Improvement in Methods of Mounting Propellers Upon Ships, of which the following description, in connection with the accompanying drawings, is a specification, like characters on the drawings representing like parts.

The invention relates to an improvement in the method of installation of the propeller upon the hull of a vessel, that is forward of 15 the stern, and in such a manner as to obviate practically all the difficulty usually encountered in vessels of ordinary construction, namely, the raising of the propeller out of the water by the rolling and pitching 20 of the vessel.

Referring to the drawings illustrating one embodiment of my invention described herein—

Figure 1 is a side view of the stern of a 25 vessel equipped with its propeller according to my novel method;

Fig. 2 a longitudinal section on the line 2—2 of Fig. 1 looking up;

Fig. 3 a cross-section on the line 3—3 Fig. 30 1 looking toward the right;

Fig. 4 a bottom view of a hull of a vessel provided with three propellers according to my novel method;

Fig. 5 a cross-sectional view of a hull 35 with three propellers, on the line 5—5 Fig. 4;

Fig. 6 a cross-section of a vessel's hull equipped with two propellers in a manner similar to Fig 4;

In Figs. 1, 2 and 3 I have shown one 40 method of mounting or installing a propeller wherein the hull 12 is provided with a transverse housing or passage-way 13 completely across the narrow lower part of the hull, which housing is, of course water tight, although the top of the housing may be provided with plates suitably secured in position so that by removal thereof, access may be had to the propeller for the installation, removal or repair of the same.

50 By housing the propeller as described at a substantial distance from the stern of the vessel, it is placed so far forward that no pitching of the vessel will bring the propeller out of water to any substantial degree. As shown, the propeller is normally just below

the water line which is identified with the section line 3—3.

This feature was suggested in my issued Patent No. 636,488, but it has been found that while the installation of the propeller as described prevented the pitching of the vessel the rear wall 14 of the housing by trapping the water itself acted as a drag upon the movement of the vessel, or the body of water in the housing was sufficient to present an appreciable drag against the forward movement of the vessel. The farther the propeller is advanced on the hull, the longer the passage across the hull necessarily is, and the longer the extent of wall to thus act as a drag. To obviate this objection I have conceived the novel idea Figs. 1, 2 of providing a passage 15 from said propeller housing rearwardly, leading out at one side of the vessel, thus permitting the water trapped in the housing to flow rearwardly and escape, thereby eliminating almost all the drag above referred to.

And again unless the propeller is located below the water line it will race when the 80 blades are raised out of the water by the rolling of the hull, just as it races when the blades are raised from the water by the forward and downward pitching of the hull. Accordingly I have located the propeller entirely below the water line, thus eliminating 85 all danger of racing from the rolling of the vessel.

In the construction in Fig. 6 where two propellers are used, the positions of the propellers being relatively near the outer wall of the hull, permits cutting away or overhanging of a portion 16 of the hull forming housings adjacent each propeller to provide ready means of egress for the water which would otherwise be trapped therein. I have also found that by installing or housing the propeller in a depressed, substantially cigar-shaped section of the hull, the propeller may be advanced materially away from the stern 100 with great advantage as in the case of the construction shown in Figs. 1 and 2, and all danger of trapping the water avoided, while substantially all the advantage of the construction shown in Figs. 1 and 2 is maintained. This may be satisfactorily accomplished by, see Fig. 4, providing the hull with the depressed overhanging areas 16.

These depressed or concave areas should be as nearly open as possible and still obtain 110

the desired amount of depression necessary to raise the propeller sufficiently, and avoid its being located too low down, and thus in effect increase the draft of the vessel. I have found that if the depression is constructed to have a flaring mouth, Fig. 5, best results are obtained, as it avoids all tendency to confine the water in a more or less inclosed channel or raceway.

10 Where the water is thus confined, the result of the pressure of the propeller blades against it is not the same as in the case where the water is substantially unconfined; and the propeller does not, under these conditions, impart to the vessel the same degree of forward impetus which is usually imparted under normal conditions. There is a certain amount of lateral displacement of the water owing to the action of the propeller blades upon it under normal conditions, and this lateral displacement of the water is not permitted when the water is confined in a channel, the walls of which are too close together so as to form substantially a raceway or conduit.

25 These walls seem to prevent lateral motion of the water under the impact of the propeller blade, with the result that there is a loss of power in the action of the propeller. 30 Apparently there should be sufficient room for free circulation of the water in all directions around the propeller following the constantly changing direction of pressure of the propeller blade upon the water owing to the 35 inclined surface of the blade, and the angle at which it contacts with the water as it rotates, and this free circulation of water is not obtained in a relatively closed channel or conduit.

40 Accordingly also for the reasons stated, the depression must not be too deep, and I

have found depressions substantially as shown in Figs. 4 and 5 to produce best results. In the construction shown in Fig. 5 where three propellers are used the channel 45 15 is not shown provided for the escape of the water near the center of the housing as in Figs. 1 and 2, the space in the rear of the propeller being open except for the overhanging section 16, the housing near the 50 outer propellers however, being cut away as in Fig. 4, to permit ready egress of the water therefrom.

Obviously with a propeller located as in Figs. 1 and 5 it is practically an impossibility for the boat to roll or pitch sufficiently to raise the propeller out of the water to any substantial degree.

Claims:

1. A ship's hull having a propeller housing relatively advanced from the stern and substantially below the water line, and a trapped water releasing passage leading from the housing rearwardly at or above the water line to provide a free passage for the 65 water from the housing under the influence of the propeller.

2. The combination with a propeller of a ship's hull having a transverse propeller housing relatively advanced from the stern 70 and substantially all below the water line to prevent racing of the propeller during the rolling of the hull, and having a trapped water releasing passage extended therefrom rearwardly at or above the water line, and 75 providing a free passage for the water from the housing under the influence of the propeller.

In testimony whereof, I have signed my name to this specification.

GEROLAMO CATANZANO.
